BRUSH FOR CLEANING BOILER AND OTHER
TUBES

Louis J. Spruzzola, United States Navy

Application May 7, 1935, Serial No. 20,196

3 Claims. (Cl. 15—198)

(Granted under the act of March 3, 1883, as
amended April 30, 1928; 370 O. G. 757)

My improved brush is economically produced and is readily refillable when the bristle units have become worn.

In the drawing, illustrating my invention, and 5 in which like characters of reference indicate the same parts:

Fig. 1 represents a perspective view of a brush body constructed in accordance with my invention;

10 Fig. 2 illustrates the finished brush.

The brush body 10 comprises a relatively long cylindrical body having projecting centrally from one end a threaded cylindrical portion 11 of reduced diameter. The opposite end of the body

15 10 is provided with a shoulder 12 of reduced diameter and relatively narrow, terminating in a shoulder 13. Centrally in the shouldered end of the body 10 is formed a cylindrical opening 15, extending substantially the length of the body 10.

20 In the shouldered end of brush body 10 are formed a plurality of pairs of relatively narrow radial open slots 14 extending through the central opening 15, through the outer surface and longitudinally of the brush body 10 to a point 25 near the opposite end of said body. The relative diameters of opening 15 and of the brush body 10 afford relatively thick walls for brush body 10 and relatively deep faces for the walls of slots 14. The width of the slots 14 is substantially the diameter of the wire or other rope 16 adapted to form the bristle units. The length of these slots 14 from the shoulder 13 to the rear 30 end of slots 14 is a multiple of the diameter of rope 16 when its coils are tightly pressed together.

35 The portions of body 10 intermediate slots 14 are keystone shaped. Bristles may be inserted in the slots 14, preferably through the open ends of each pair of slots, until the slot is filled to the shoulder 13. The bristles preferably are of a continuous length extending from a point beyond the diameter of brush body 10 through one of the slots 14 and about the sharp inner edges of the keystone-shaped portions of the body 10 between adjacent slots and extending through the adjacent slot to a point beyond the periphery of body 10. These points where the bristles terminate comprise the brush or cleaning surface of the brush, as indicated in Fig. 2. When the 40 slots 14 are filled with bristles, collar 20 is forced over the shoulder 12 of body 10 and against shoulder 13 thereof. In such position, collar 20 presses the coils tightly together in their respective slots 14.

55 The bristle units are securely held in their

brushing positions by the tightness with which the side walls of slots 14 engage the portions of rope 16 therein, and by the force with which ring 20 clamps the rope portions longitudinally in slots 14, as well as by the sharp bends of the rope portion at the interior corners of the keystone-shaped portion of body 10. The length of brush body 10 and the depth of slots 14 afford some outward spring to the keystone-shaped portions of body 10 when the coils are inserted or formed thereabout, and the collar 20, when in position, prevents such spring and insures the rigid holding of the rope portion between the walls of slots 14.

5 The diameter of projection 12 of brush body 10 and the internal diameter of ring 20 are slightly tapered so that the ring 20, when inserted on to projection 12 and forced into contact with shoulder 13 of body 10, will cause the keystone-shaped portions of body 10, between the slots 14, to be moved slightly inward. This inward motion clamps the bristles tightly in their respective slots 14 and holds them so rigidly that the cleaning surface formed by the adjacent ends of the bristles may function more efficiently in cleaning. The taper of the ring 20 upon the shoulder 12, together with the inward pressure of the keystone-shaped portions of body 10 maintained by ring 20 and its tapered bore, forms a very efficient securement for the slotted end of the brush body 10 as well as an efficient end clamp upon the bristles in each of the slots 14.

20 This application is for subject matter disclosed in application No. 661,116, of which this applicant was the sole inventor and for the purpose of leaving in said application only the subject matter of the sole invention of Lieutenant-Commander Edgar P. Kranzfelder.

25 The invention described herein may be manufactured and used by or for the Government of the United States of America for governmental purposes without the payment of any royalty thereon.

Having so fully shown and described my invention that others may therefrom make and use the same, what I claim and pray to secure by Letters Patent is:—

30 1. A brush including a cylindrical body, a central longitudinal cylindrical projection on one end of and less in diameter than said body, said body and projection provided with longitudinal slots transverse to and communicating with one another, and leaving sector-like portions of the body between the transverse slots, wire bristles doubled upon themselves to provide pairs of angu- 35

larly arranged tufts, said pairs of tufts being seated in the slots with the tufts of each pair extending outwardly through adjacent slots and the connecting portions of said tufts of each pair between said slots being in communication between said slots, and a ring of a width substantially that of the length of and adapted to fit over said projection with its adjacent edge closing the outer end of, and confining said tufts in, each of said slots.

2. A brush including a cylindrical body, said body provided with longitudinal slots transverse to and communicating with one another within the outer diameter of said body, and leaving sector-like portions of the body between the transverse slots, wire bristles doubled upon themselves to provide pairs of angularly arranged tufts, said pairs of tufts being seated in the slots with the tufts of each pair extending outwardly through adjacent slots and the connecting portions between said tufts extending between said slots in the interior of said body, a projection of

said body upon the slotted end thereof being of reduced diameter and having a shoulder upon the inner end thereof, the periphery of said projection being tapered, slightly less in diameter at its outer than at its shouldered end, and a ring having a correspondingly tapered bore adapted to fit upon said projection and against said shoulder for securing the sector-like portions together at their outer ends and clamping the bristle units in their respective slots.

3. A brush comprising a cylindrical body having a tapered projection upon at least one end thereof, slots formed through said body and extending from the outer end of said tapered portion to a point near the opposite end of said body, said slots being adapted to receive bristle material, and a relatively thin, long ring having a tapered bore cooperating with the taper of said projection for inwardly moving portions of the cylindrical body intermediate said slots and clamping the bristle material in said slots.

LOUIS J. SPRUZZOLA.
